UNITED STATES PATENT OFFICE.

HERBERT S. HUMPHREY, OF KALAMAZOO, MICHIGAN, ASSIGNOR TO RUUD MANUFACTURING COMPANY, OF PITTSBURGH, PENNSYLVANIA, A CORPORATION OF NEW JERSEY.

DESIGN FOR A WATER-HEATER BODY.

46,252.

Specification for Design.

Patented Aug. 11, 1914.

Application filed June 4, 1914. Serial No. 843,099. Term of patent 14 years.

To all whom it may concern:

Be it known that I, HERBERT S. HUMPHREY, a citizen of the United States, and residing at Kalamazoo, in the county of Kalamazoo and State of Michigan, have invented a certain new, original, and ornamental Design for a Water-Heater Body, of which the following is a specification, reference being had to the drawing forming a part thereof

and illustrating my new design in perspective.

I claim:—

The ornamental design for a water heater body, substantially as shown.

HERBERT S. HUMPHREY.

Witnesses:

F. A. LEMKE,

B. M. SCHERER.
